WINDOW SHADE

Filed July 24, 1931

INVENTOR
Joseph Roscia
BY
Zoltan Polachek
ATTORNEY

UNITED STATES PATENT OFFICE

JOSEPH ROSCIA, OF BROOKLYN, NEW YORK

WINDOW SHADE

Application filed July 24, 1931. Serial No. 552,882.

This invention relates to new and useful improvements in a shade hanging.

The invention proposes to adjustably support a shade support slide so that the roller portion of a shade may be suspended at various positions upon a window. This arrangement allows a shade to be drawn from its uppermost position or some intermediate position.

10 A still further object of this invention is the provision of guide members upon the sides of a window frame, slides arranged in said guide members and formed for receiving the trunnions of a roller in a window shade, and means for adjustably holding the shade support slides at various elevated positions.

As another object of this invention it is proposed to arrange cables connected with 20 the slides and extended over pulleys terminating adjacent each other so that they may be simultaneously drawn and change the position of the shade support slides.

Furthermore, the invention proposes socket members adjustably mounted in the shade support slides in a manner so that the slides must be moved to different elevations before the shade can be removed from place.

Another one of the objects of this invention 30 is the construction of a shade hanging which is of simple, durable construction, dependable in use and efficient in action, and which can be manufactured and sold at a reasonable cost.

35 For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

45 Fig. 1 is a front elevational view of a window provided with a shade hanging according to this invention.

Fig. 2 is a view similar to Fig. 1 but showing the shade roller lowered.

50 Fig. 3 is a fragmentary enlarged sectional view taken on the line 3—3 of Fig. 2.

Fig. 4 is a fragmentary elevational view looking in the direction of the line 4—4 of Fig. 3.

Fig. 5 is a horizontal sectional view taken on the line 5—5 of Fig. 1.

Fig. 6 is a fragmentary enlarged sectional view taken on the line 6—6 of Fig. 3.

Fig. 7 is a view similar to Fig. 6 but showing the shade support slide on the opposite side of the window.

Fig. 8 illustrates a sectional view of a modified form of shade support slide.

The shade hanging, according to this invention, is for use in conjunction with a window frame 10. Guides 11 are attached upon the inner sides of the frame 12 and extend from near the top downwards to any desired amount. These guides comprise sheet metal bent with their edges slightly spaced from each other.

A pulley 12 is supported over one of the guides 11. A compound pulley 13 is supported over the other guide 11. This compound pulley has a pair of rollers adjacent each other. A cable 14 extends over the pulley 12 and one of the rollers of the compound pulley 13. A second cable 15 extends over the other roller of the compound pulley 13.

Both of these cables run downwards along one side of the window frame and through guide eyelets 16. The adjacent portions of these cables are formed with common knots 17 so as to be engageable over hook 18 projecting from the lower end of one of the guides 11.

This hook is formed by bending the material of the guide at an inclination, as clearly shown in Fig. 1, and forming a cut therein as shown in Fig. 3. The free end of the cable 14 connects with a shade support slide 19 mounted within the guide 11.

The free end of the cable 15 connects with a shade support slide 20 mounted in the other of the guides 11.

The slide 20 is formed with a circular recess 21 for receiving the conventional peg end of the roller of a shade 22. The shade support slide 19 is formed with a slot 23 for receiving the conventional winding stem portion of the roller shade 22.

In Fig. 8 a modification of the invention has been disclosed in which a shade support

slide 24 is provided working within the guide 11. The slide 24 is formed with a central hollow portion 25 in which a socket 26 is pivotally supported by trunnions 27. The socket 26 is formed with an opening 28 for receiving a peg 29 from the roller of the shade 30. It is intended that the roller of the shade be provided with pegs 29 at both ends and that two of the shade support slides 24 be provided, one in each of the guides on opposite sides of the window frame. To remove the shade 30, it is necessary that the shade support slides 24 which support the shade be elevated to different heights. This can be done by pulling one of the cables which supports the slide and hold the other one stationary. The pivoting of the socket 26 will compensate for the angle at which the shade is moved. When the shade support slides 24 have been moved to a sufficient different elevation, the shade will be free.

The operation of the device consists in the manual control of the cables 14 and 15 at the hook portion 18 for the purpose of changing the elevation of the shade roller. The shade itself can be moved as is conventional, that is drawn to any desired amount. The adjustability of the positions of the shade roller allows positioning of the shade, for example, as shown in Fig. 2 where the upper portion of the window is opened and only the lower portion covered.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:—

1. In a supporting slide for vertically adjustable rollers, a slide member with an opening, a socket member pivotally mounted in said opening and formed with an aperture for engaging a pintle of a shade roller.
2. In a supporting slide for vertically adjustable rollers, a slide member with an opening, a socket member for engaging a pintle of a roller shade, and means for pivotally supporting the socket member within the opening formed in the slide member.
3. In a supporting slide for vertically adjustable rollers, a slide member with an opening, a socket member for engaging a pintle of a roller shade, and means for pivotally supporting the socket member within the opening formed in the slide member, comprising trunnions pivotally supporting said socket member.

In testimony whereof I have affixed my signature.

JOSEPH ROSCIA.
